UNITED STATES PATENT OFFICE.

WILLIAM T. MARCOTT, OF OLYMPIA, WASHINGTON, ASSIGNOR TO MARCOTT AUTO SIGNAL COMPANY, OF OLYMPIA, WASHINGTON, A CORPORATION OF WASHINGTON.

SIGNALING DEVICE.

Application filed July 5, 1921, Serial No. 482,596. Renewed January 22, 1927.

This invention relates to direction signals for vehicles and, more especially, to improvements in the apparatus illustrated and described in patent application Serial No. 5 458,359 filed by me April 4, 1921.

The object of my improvements is to perfect the above mentioned apparatus so as to render the same more efficient in operation and to enable the driver to more effectively indicate his intentions of turning or stopping his car.

Other objects and advantages of the invention will appear from the following specification.

15 The invention consists in the novel construction, arrangement and combination of parts hereinafter described and claimed.

In the accompanying drawings,—

Figure 1 is a vertical transverse section 20 of an automobile signaling device embodying my improvements, the electrical circuit connections thereof being shown diagrammatically. Fig. 2 is a horizontal section through 2—2 of Fig. 1.

25 In said drawings, the reference numeral 5 designates a casing member having in the front and rear thereof sight openings, such as indicated by broken lines 7, for which are provided glass panes or lenses. At one 30 side of said casing member is a communicating chamber 8 provided in a bracket piece 9 which is rigidly secured to the casing. Said bracket is provided with a globular arm 10 which engages in the socket 12 of a clamping member 13 which is adapted to be secured to a side bar 14 of a windshield.

35 Journaled in a boss element 15 of the bracket 9 is a stub shaft 16 upon which is mounted within said casing a cylindrical cage 17 whose peripheral wall is composed of a plurality of elements 18 and 19 of differently colored transparent or semi-transparent material such, for example, as celluloid.

40 45 50 55 20 represents an electric motor located in the casing chamber 8 and serves, upon occasion, to rotate said cage as by means of a spur pinion 21 on the armature shaft engaging internal gear teeth 22 provided on the cage. Connected to the outer end of the casing member 5 is a socket 23 for an electric lamp 24.

The above described parts are or may be constructed and arranged as explained in the patent application above referred to and

afford means to produce successive beams of light of different colors to attract attention to the hereinafter described direction signaling devices which constitute the subject matter of the present invention. 60

In carrying out my improvements, I provide a casing member 25, preferably cylindrical, which depends from the aforesaid member 5 and is provided in the front and rear thereof with sight apertures such as 26 65 which are desirably closed by transparent glass panes.

Within the chamber 27 of the casing member 25 is an electric lamp 28. Suspended from and rotatably mounted in the top wall 29 of said chamber is a vertical shaft 30 which supports a disk 31. 70

The disk 31 serves, in turn, to support a circular translucent partition or shield 32 which is painted or otherwise provided on its inner surface with a plurality of circumferentially spaced sign characters R, S and L, such as denoted by 33. Each of these sign characters is, moreover, advantageously provided in duplicate, corresponding characters being disposed at diametrically opposite sides of the shield so that similar characters will be presented simultaneously at the sight apertures 26 in the front and rear of the member 25 to become visible when illuminated by the action of lamp 28. 75 80 85

The shaft 30 is provided with an arm 36 which is connected by opposing springs 37 with studs 38 secured to the partition 29, said springs serving to yieldingly retain the shield 32 in its rotary position whereat the stop characters "S" thereon will be opposite the respective sight apertures. For rotating the shield to present the right or left turning signals to an observer, I provide a 90 system of electric magnets comprising solenoid coils 34 and 34¹ at opposite sides of shaft 30 and rigidly secured to the partition 29. 95

The core or armature 35, common to both 100 of said magnets, is secured to the arm 36 so that the latter together with the rotary shield will be turned when one or the other of said coils is energized selectively.

An electric system for supplying current 105 to actuate the above described signal devices, as illustrated diagrammatically in Fig. 1, comprises an electric battery 40 which is connected by circuit wire 41 and a branch 42 thereof with the filaments of the respec- 110

tive lamps 24 and 28 whence return connections 43 and 44 lead to a main wire 45 from which extend leads to terminals 46, 47 and 48 for a switch member 49 which is connected by wire 50 with the battery.

The circuit wires 41 and 45 are respectively connected by wires 51 and 52 with the motor 20. The magnet coil 34 is connected by a branch lead 53 with the wire 43 and also by a return wire 54 with a terminal 55 disposed adjacent to the terminal 48. The other magnet coil 34¹ is connected with the wire 51 by means of a branch lead 56 and by a return wire 57 with a terminal 58 disposed adjacent to the terminal 46. Normally, the switch member 49 would be disposed out of contact with all of the terminals causing the lamps to be inoperative and enabling the springs 37, Fig. 2, to retain the shield 32 in position to have the stop indicating characters "S", denoted by 33¹ in Fig. 1, opposite the respective sight apertures. To signal the driver's intention to stop the vehicle, the switch member 49 is brought into contact with the terminal 47 to accordingly complete the motor circuit and both of the lamp circuits whereby the multiple colored cage is rotated and illuminated and the light from the lamp 28 renders the stop letter "S" visible.

When it is desired to give notice of intention to turn the vehicle to the left or right, the switch member is moved by the driver into position to bridge the gap between the proper pairs of terminals 46—58 or 48—55.

to close the circuit for a current to the appropriate magnet coil to energize the same whereby the core 35 is influenced to effect the rotation of the shield 32 to present the characters "L" or "R" in positions to be seen 40 through the instrumentality of the light provided by the lamp 28.

It is to be noted that the cage 17 is rotated and both lamps are caused to produce light in each of the three signaling positions 45 of the rotary shield 32.

What I claim, is,—

In a signaling device for automobiles, a cylindrical bracket piece having one closed end, a globular mounting arm projecting outwardly from the closed end, a boss, having a bore, carried by the closed end of the bracket piece and projecting through the bore of the latter, a substantially spherical casing having a cylindrical communicating 50 projection receiving and fastened to the cylindrical bracket piece, said casing having sight openings, a cylindrical signal cage having a stub shaft journaled in the bore of the boss and arranged within the casing for being viewed through the sight openings of the latter, an internal ring gear concentric with and projecting from one end of the cage, and an electric motor mounted within the cylindrical bracket piece and having a 55 pinion meshing with the ring gear on the cage.

Signed at Olympia, Washington, this 22nd day of June 1921.

WILLIAM T. MARCOTT.
